MILES B. DODGE, OF BROOKLYN, NEW YORK.

Letters Patent No. 90,510, dated May 25, 1869.

IMPROVEMENT IN ORE-CRUSHERS.

The Schedule referred to in these Letters Patent and making part of the same

To all whom it may concern:

Be it known that I, MILES B. DODGE, of Brooklyn, in the county of Kings, and State of New York, have invented a new and improved Apparatus for Crushing Minerals, Ores, and Rocks; and I do hereby declare the following to be a full, clear, and exact description thereof, which will enable those skilled in the art to make and use the same, reference being had to the accompanying drawing, forming part of this specification, in which drawing—

Figure 1 represents a transverse section of this invention.

Figure 2 is a sectional plan thereof.

Similar letters indicate corresponding parts.

This invention relates to a roller-crusher in which the ordinary chilled cast-iron or steel rollers are replaced by wrought-iron rollers, or by cast-iron rollers faced with wrought-iron, whereby the most serious disadvantages attending said ordinary rollers are obviated, and a crusher is produced, the rollers of which will draw in the quartz or other material to be crushed, instead of squeezing it back; and furthermore, the crushing-surfaces of said rollers are not liable to become rugged by the action of the quartz or other hard materials passing through between them, whereas the surfaces of the rollers, as usually made, of chilled cast-iron or steel, soon become rugged and uneven, since extra hard pieces of the quartz or other rock to be crushed are liable to carry off small chips of the hard rollers, which is not the case with the rollers made of or faced with wrought-iron.

My crushing-apparatus does not differ in form or shape from an ordinary roller-crusher.

It is composed of two rollers, A A, which have their bearings in a strong frame, B, the bearings of one of the rollers being made adjustable, so that the distance between the crushing-surfaces can be adjusted to suit circumstances.

Usually the crushing-rollers are made of chilled cast-iron, and sometimes of steel, and if a piece of quartz or other hard material is placed upon such a roller, it is liable to slip thereon, and in many cases it is very

difficult to cause such a hard piece to enter between the crushing-surfaces. With my rollers, made of or faced with wrought-iron, this difficulty is obviated.

If a hard piece of quartz is placed on them, they, being provided with a comparatively soft and yielding surface, catch hold of said piece, and draw it in without permitting it to slip, and while passing through between the crushing-surfaces, the operation of crushing is effected.

Furthermore, if the crushing-rollers are made of chilled cast-iron or other very hard material, and a very hard piece of quartz, or a chisel, or other hard substance, passes through between them, it happens many times, that pieces of the crushing-surfaces become rugged and uneven; but if the rollers are made of or faced with wrought-iron, and a very hard piece of quartz, or a chisel, or other hard substance, is made to pass through between them, the iron of the rollers yields, and is pressed on one side, leaving a depression at one, and a protuberance at the adjoining place, and by another piece passing through the rollers, perhaps the protuberance formed is pressed back again, and the evenness of the rollers is restored.

In short, the advantages of my rollers, made of or faced with wrought-iron, over the ordinary chilled cast-iron or steel rollers, are, in many respects, the same as the advantages of my wrought-iron crushing-faces, in crushers for which a patent was granted to me, December 4, 1866, numbered 60,154.

Having thus described my invention, what I claim as new, and desire to secure by Letters Patent, is—

The application of soft wrought-iron faces to the rollers of a quartz-crusher, as and for the purpose herein set forth.

This specification signed by me, this 25th day of March, 1869.

MILES B. DODGE.
